AGITATING TANK FOR LIQUIDS

George S. Witham, Jr., Portland, Oreg.

Application October 25, 1937, Serial No. 170,838

6 Claims. (Cl. 259—95)

This invention relates to means for agitating liquid in a tank and is designed for tanks used for mixing pulp in the process of paper manufacture, or for mixing chemicals in solution. The invention concerns the treatment of pulp, or the treatment of any liquid requiring circulating and agitating in tanks, vats, tubs, etc., of any capacity.

Referring specifically to the use of my invention in connection with the treatment of pulp, when pulp in the ordinary liquid state is maintained or mixed in tanks or tubs, the pulp must be kept in constant circulation or agitation, or else the pulp fibers, which will ordinarily float in water, will have the tendency to collect in masses at the top which prevents proper mixing and treating of the pulp at this point of the process. This problem increases with the increased height or depth of tanks or tubs. On the other hand, due to the desirability of economizing floor space and to structural advantages and economies, it is desirable to maintain the pulp during this period in large tanks, preferably cylindrical in shape, and of considerable height.

One of the means which has been tried for keeping pulp in proper circulation in tanks of any height has been the setting up of a circulating propeller on a vertical axis close to the bottom of the tank. This has not been found entirely satisfactory and has also involved some difficulties of construction. Another means which has been invented for causing proper agitation and circulation in a high tank is a series of pumps located in the tank at different levels.

I have found it is possible, however, to meet the problem more efficiently without the necessity of establishing such circulating means at different levels in the tank. The object of my invention is accordingly to provide a simple means, located at a single level, for producing this necessary agitation and circulation of liquid in a tank.

Another object of my invention is to provide means of this type to be located at the bottom of the tank and so arranged that it will function efficiently regardless of the level of the liquid in the tank.

These objects I attain by providing the propeller or circulating means within the tank, adjacent the bottom thereof, and associated with a "mid-feather"; and by combining with this circulating means an inclined bevel or "back-fall" which will act so as to force the circulating current produced in the liquid within the tank to include the upper surface of the liquid in its path at all times.

The manner in which I carry out my inven-

tion and accomplish these and incidental objects will be apparent from the following description with reference to the accompanying drawings.

In the drawings:

Fig. 1 is a sectional plan on the line 1—1 of Fig. 2;

Fig. 2 is a sectional elevation on the line 2—2 of Fig. 1;

Fig. 3 is a sectional plan on the line 3—3 of Fig. 4 illustrating a modification in construction; 10

Fig. 4 is a sectional elevation on the line 4—4 of Fig. 3; and

Fig. 5 is a partial sectional elevation corresponding to Fig. 2 but showing an alternative 15 circulating means.

Referring first to the form of my invention as illustrated in Figs. 1 and 2, the outer wall of the tank is indicated by 1. I have shown the tank as substantially cylindrical, which I consider the preferred shape. The tank also includes a dome 20 top 2, inclined floor 3 and suitable supporting base 4. The interior of the tank is provided with a divided partition or "mid-feather" 5 comprising an end wall 6 and curved side walls 7 and 8, which extends the full height of the tank and forms a rigid structure of horse-shoe shaped cross-section, as illustrated in Fig. 1. The "mid-feather" 5 is preferably so placed that the center line distance between the end wall 6 thereof and the adjacent portion of the outer wall 1 is considerably less than the distance from the extremities 9 and 10 of the curved walls 7 and 8, respectively, to the adjacent portion of the outer wall 1; thus the passages 11 and 12 are formed between the curved walls 7 and 8 and the outer wall, which passages gradually decrease in width as they approach the end wall 6 of the "mid-feather" where these passages converge.

The end wall 6 of the "mid-feather" has a circular aperture at the base in which is located the 40 impeller or circulating element. This circulating element preferably comprises a propeller 14 mounted on a horizontal shaft 17. The shaft 17 passes through the outer wall of the tank and is journaled in suitable bearings such as indicated 45 at 18, 19 and 19'. This shaft 17 is in axial alignment with the longitudinal center line of the "mid-feather". Any suitable means for providing a fluid tight joint at the wall bearing 19 may be employed. The shaft 17, and with it 50 the propeller 14, are driven by any suitable means, for example by a motor indicated at 15.

Curving upwardly from the base at the bottom of the end wall 6 and within the space of the "mid-feather" is a baffle or "back-fall" 20 which 55

extends across the space between the curved walls 7 and 8 of the divided "mid-feather". This "back-fall" 20 is parallel to the end wall 6. The remaining portion 21 of the tank floor lying 5 within the "mid-feather" slopes downwardly from the rear face of the "back-fall" as shown in Fig. 2. This downward slope continues in the floors of the passages 11 and 12 and the floors of both of these passages decline in the direction 10 indicated by the arrows in Fig. 1 toward a sump 22 which is recessed in the floor of the tank and in which is located the tank outlet pipe 23. Thus the entire fluid contents of the tank may be drained by gravity.

15 The tank wall 1 is preferably formed with an internal vertical ridge or diverging baffle 13, in alignment with the longitudinal center of the "mid-feather" and equi-distant from the ends 9 and 10 of the walls 7 and 8 of the divided "mid-feather", as shown in Fig. 1.

20 The inlet pipe for the tank is preferably located in the domed cover 2 above the propeller shaft 17 and between the end wall 6 of the "mid-feather" and the outer wall of the tank, as shown 25 in Fig. 2, so that the pulp entering the tank will be drawn down by the action of the propeller 14 and into the interior of the tank thru the aperture in the base of the wall 6.

25 Due to the upwardly curving slope of the face 30 of the "back-fall" 20, opposite the propeller 14, the pulp drawn thru the aperture in the wall 6 by the action of the propeller will be forced upwardly as well as forward in the tank, and will follow the course indicated by the arrow in Fig. 2 and subsequently by the arrows in Fig. 1. Thus 35 the resultant effect brought about by the upwardly sloping face of the "back-fall" is to cause circulation and agitation of the top surface of the liquid in the tank as well as thruout the other 40 portions of the liquid. This constant circulation of the water and pulp thruout the entire volume of the liquid prevents any collection of the pulp fibers in the form of so-called curds or islands of pulp fibers in the top of the tank and similar settling 45 of the water at the bottom of the tank. As the pulp, due to the combined influence of the propeller 14 and the sloping surface of the "back-fall" 20, is forced upward and forward in the space within the divided "mid-feather", the current 50 is divided by the diverging baffle 13 and part directed thru the passageway 12 and part thru the passageway 11 to the opposite side of the tank when it is again drawn thru the aperture in wall 6 by the action of the propeller. The decreasing 55 width of the passageways 11 and 12 retards this flow of the pulp and consequently enhances the downward surging action caused by the suction of the pulp again thru the aperture at the base of wall 6.

60 The modified form of my invention shown in Figs. 3 and 4 is similar in construction and operation to that shown in Figs. 1 and 2 but a substitution of two propellers and two "back-falls" of different heights is provided for the purpose of obtaining still greater agitation of the pulp in the tank. In this modification the wall 6 of the "mid-feather" has two apertures at the base for the purpose of accommodating two propellers 25 and 25', which are mounted on parallel shafts and driven by motors 26 and 26' or by any other 65 suitable means. In place of the single "back-fall" 20 of Figs. 1 and 2 I provide two "back-falls" 27 and 27', in alignment with each other and each extending half the distance across the space 70 between the curved "mid-feather" walls 8 and 7.

The slopes of the faces of these two "back-falls" opposite the propellers are similar and the surfaces coincide, but "back-fall" 27' is preferably made to extend approximately twice the height of the "back-fall" 27. With this modified construction I obtain a greater upward surge in half of the space within the "mid-feather", than in the other half, which I have found results in a greater mixing action within the "mid-feather", which is desirable particularly for high tanks and 10 tanks with larger capacities where the propellers are located at considerable depth below the top surface of the pulp. In all other respects the results obtained are similar to those already described with reference to the construction illustrated by Figs. 1 and 2.

15 Referring now to Fig. 5, a rotary pump 28 may be used as a circulating and agitating means instead of the motor driven impellers of the previous embodiments. The fluid in the tank is 20 drained by gravity into the sump 29 provided in the sloped floor 3 of the tank and connected with a pipe line 30 leading to the pump 28. A branch pipe 30' controlled by a stop valve 31 provides a means for withdrawing pulp from the tank 25 or for draining the tank when the pump is not in use. With the valve 31 closed and the pump 28 operating, the fluid is drawn from the tank into the pipe 30 and then forced back under high pressure into the said tank thru a pipe 32 which 30 passes thru the outer tank wall 1 and is disposed in an aperture of suitable size provided in the partition end wall 6 substantially as shown. The same results is thus obtained as with the agitating elements previously mentioned, the fluid 35 exhausting at high velocity from the return pipe 32 against the "back-fall" 20 causing upward surging and constant surface agitation. With this modified form of my invention there is the advantage of having the circulating medium located outside of the tank, making it possible to 40 repair the circulating medium without draining the tank.

45 While it would be possible to increase the number of apertures and propellers located at the bottom of the "mid-feather" wall 6, in my opinion nothing would be gained by so doing, and I have found that one or two propellers, of proper diameter, pitch, and speed, in combination with a "back-fall" or "back-falls", as the case may 50 be, arranged substantially as I have indicated, will prove ample and efficient for tanks of all practical capacity. Although I have described my invention chiefly in connection with a tank containing pulp, its use would be the same with 55 any liquid materials. The tank which I have shown in the illustrations is circular or cylindrical, but it is obvious that an elliptical or even a rectangular tank might be substituted. Also obviously other modifications might be made in 60 the construction, such as changes in the shape and position of the "mid-feather", without departing from the principle of my invention. It is not my intention to limit myself to any particular construction provided that the essential 65 features, namely, an impelling means in combination with upwardly sloping "back-fall" of sufficient height are located at or near the bottom of the tank.

70 I claim:

1. In a tank for materials in liquid form a "mid-feather" partition, a plurality of apertures in said "mid-feather" located near the bottom of said tank, a liquid circulating element located in each of said apertures, a plurality of "back- 75

falls" in the bottom of said tank located in front of said circulating elements, respectively, said "back-falls" being of different heights, whereby the liquid driven thru said apertures by said 5 circulating elements will be directed upwardly and forwardly thru the central portion of said tank, and agitate the top surface of the liquid as well as other portions of the liquid in said tank.

2. A circular tank for materials in liquid form including a U-shaped "mid-feather" partition, a pair of apertures in said "mid-feather" located near the bottom of said tank, an impeller located in each of said apertures, means for operating each of said impellers, a pair of "back-falls" in the bottom of said tank located in front of said impellers, respectively, said "back-falls" being of different heights, whereby the liquid driven thru said apertures by said impellers will be directed upwardly and forwardly thru the 15 central portion of said tank, and agitate the top surface of the liquid as well as other portions of the liquid in said tank.

3. A tank for materials in liquid form comprising a curved "mid-feather" partition spaced 20 from the outer wall of said tank, the distance between said "mid-feather" and the wall of said tank decreasing towards the center of said "mid-feather" whereby to form two converging passageways of decreasing width between the tank 25 wall and said "mid-feather", an aperture in the center of said "mid-feather" located near the bottom of said tank, a "back-fall" on the bottom of said tank extending across the space within said "mid-feather", said "back-fall" extending above 30 said aperture, means for impelling the liquid in said tank through said aperture and against said "back-fall", the floor of said tank, within the space enclosed by said "mid-feather", sloping downwardly from said "back-fall", and said 35 40 downward slope of the tank floor continued in opposite direction in said converging passageways.

4. In a tank for materials in liquid form, a U-shaped "mid-feather" partition spaced from the outer wall of said tank, an aperture in the center of said "mid-feather" located near the bottom of said tank, a "back-fall" on the bottom of said tank extending across the space within said "mid-feather", the face of said "back-fall" opposed to said aperture sloping upwardly and extending to a height above said aperture, the opposite face of said "back-fall" sloping downwardly to the bottom of said tank, and the floor of said tank between said "mid-feather" and said "back-fall" sloping downwardly. 5 10

5. In a tank for materials in liquid form, a U-shaped "mid-feather" partition spaced from the outer wall of said tank, an aperture in the center of said "mid-feather" located near the bottom of said tank, a "back-fall" on the bottom of said tank extending across the space within said "mid-feather", the face of said "back-fall" 15 opposed to said aperture sloping upwardly and extending to a height above said aperture, the opposite face of said "back-fall" sloping downwardly within the space inclosed by said "mid-feather" to the bottom of said tank, and means 20 25 for impelling the liquid in said tank thru said aperture and against said "back-fall".

6. In a tank for materials in liquid form, a "mid-feather" partition, the ends of said "mid-feather" partition spaced from the walls of said 30 tank, an aperture in the center of said "mid-feather" located near the bottom of said tank, means for impelling the liquid in said tank thru said aperture, a "back-fall" on the bottom of said tank located ahead of said aperture, the 35 face of said "back-fall" opposed to said aperture sloping upward beyond the height of the top of said aperture, the other face of said "back-fall" sloping downward to the bottom of said tank, the bottom of said tank sloping downward from said 40 "back-fall".

GEORGE S. WITHAM, JR.
